UNITED STATES PATENT OFFICE.

RALPH A. STANLEY, OF GLADSTONE, ILLINOIS.

INVALID-BEDSTEAD.

1,104,300.

Specification of Letters Patent. Patented July 21, 1914.

Application filed March 21, 1914. Serial No. 326,344.

To all whom it may concern:

Be it known that I, RALPH A. STANLEY, a citizen of the United States, residing at Gladstone, in the county of Henderson and 5 State of Illinois, have invented certain new and useful Improvements in Invalid-Bedsteads, of which the following is a specification.

The bedstead which is the subject matter 10 of the present application for patent is designed more particularly for invalids, and the object of the invention is to provide a bedstead which is so constructed that the occupant thereof can be readily lifted or 15 moved about for the purpose of changing the bedding or other parts, and attending to the wants of the occupant.

The invention also has for its object to provide a bedstead which is perfectly sanitary, and also simple and cheap in construction.

Other objects and advantages will be pointed out in the detailed description appearing hereinafter, and in order that the 25 invention may be better understood, reference is had to the accompanying drawings, in which—

Figure 1 is a plan view of the bedstead, partly broken away and in section; Fig. 2 30 is a cross-section on the line 2—2 of Fig. 1; Fig. 3 is a side elevation of the bedstead partly broken away and in section; Fig. 4 is a horizontal section on the line 4—4 of Fig. 3; Fig. 5 is a cross-section of the bedstead on the line 5—5 of Fig. 1, and Figs. 6 and 7 are sectional details on the lines 6—6 35 and 7—7, respectively, of Fig. 1.

Referring specifically to the drawing the bedstead proper comprises head and foot 40 sections 10 and 11, respectively, and side rails 12 connecting the same. The head section has a top cross bar 13, and the foot section a top cross bar 14. This structure is mounted on a pedestal comprising a stationary cylinder 15 mounted on the floor, and a hollow plunger 16 working in said cylinder and carrying the bedstead, which latter is adapted to be raised or lowered by sliding the plunger in the cylinder. The 45 top of the plunger is closed by a plate 17 at the center of which is a bearing 18 in which is stepped a pivot 19 extending downward from the bottom of a plate 20 secured to and connecting the rails 12. The bedstead 50 is thus swiveled to the plunger and it may

be swung around in a horizontal plane to facilitate access to either side thereof. The plate 17 carries anti-friction rollers 21 which engage the under side of the plate 20.

The plunger 16 is operated to raise or 60 lower the bedstead, by means of a non-traveling screw 22 supported in upright position by a cross bar 22^a mounted in the cylinder 15 and threaded through a nut 23 at the center of a spider 24 secured inside the plunger. The screw is actuated by a gearing comprising a bevel gear 25 in mesh with a similar gear 26 on the lower end of the screw. The gear 25 is on a shaft 27 journaled in the wall of the cylinder and having at one 70 end, on the outside of the cylinder, a hand-wheel 28, and a pawl-and-ratchet mechanism 29 for preventing the shaft from slipping. The wall of the plunger has slots 30 to accommodate the cross bar 22, these 75 parts also serving to prevent the plunger from rotating in the cylinder.

The plate 17 is circular and has notches 31 in its periphery engageable by locking dogs 32 carried by the plate 20, whereby the 80 bedstead may be locked after it is swung around to the desired position.

On the corner posts of the head and foot sections 10 and 11 is slidably mounted a lifting or carrier frame composed of side rails 85 33 and end rails 34 connecting the same. At the junction of the rails are socket pieces 35 through which the corner posts pass, whereby the frame is slidably supported by said posts so that it may be raised or lowered. 90

Inside the lifting frame is held stretched a sheet 36 of canvas or other suitable strong material, said sheet being secured at its longitudinal edges to rollers 37 journaled in the end rails 34. To the ends of the rollers 95 are attached crank-handles 38 for rotating the former to wind the sheet thereon and thus keep the same tightly stretched. Pawl-and-ratchet devices 39 are provided to prevent the rollers from slipping. In the sheet 100 is a hole 40 for a vessel.

The following means are provided for raising and lowering the lifting frame: On the top cross bars 13 are mounted sheaves 41 over which pass hoisting lines 42. To 105 the end rails 34 are anchored coiled springs 43. The lines 42 pass downward from the sheaves and are connected at one of their ends to the springs. The other ends of the lines extend downward to the pulleys 44 110

mounted on cross rails 45 connecting the corner posts of the head and foot sections of the bedstead. After passing over the last-mentioned pulleys, the lines are carried forward toward the middle of the bedstead and wound on rollers 46 extending transversely between and supported by the side rails 12 of the bedstead. These rails also support a transverse shaft 47 which is geared at 48 to the rollers 46 so that when said shaft is rotated, both rollers are rotated to wind up or pay out the lines 42. Both ends of the lifting frame are therefore elevated or lowered uniformly and said frame is kept level. On each end of the shaft 47 is a hand wheel 49 for operating the same, and a pawl-and-ratchet device 50 for preventing the shaft from slipping is also provided.

By means of the springs 43 the lifting frame is spring-supported and the patient is not jarred when said frame is elevated or lowered.

The lifting frame also carries a head rest which is adjustable lengthwise of said frame so that the patient may be brought back if there is a tendency for the patient to slip down in the bed. This head rest comprises a slideable frame having side rails 51 which are angular in cross-section so that they may be mounted on the side rails 33 of the lifting frame. The side rails 51 carry rollers 52 which travel along the top and bottom edges of the rails 33. The head ends of the rails 51 are connected by a cross-rail 53. At the head end of the side rails 51, the top flanges thereof have apertures 54 into selected ones of which are adapted to be inserted upwardly curved resilient strips 55 connected at their upper ends by a cross-rod 56. The head rest frame is covered by a sheet 57 which also extends between the strips 55 and up to the cross-rod 56, the side rails 51 and the strips 55 having buttons or other suitable fasteners 58 by which the sheet is removably secured.

As the strips 55 are resilient they may be swung up or down to raise or lower that part of the sheet which extends therebetween. The strips may also be adjusted lengthwise of the side rails 51, a series of apertures 54 being provided for this purpose. The tendency of the strips 55 is to spring upward, and they are held in adjusted position by a strap 59 connecting the cross-rail 53 and the cross rod 56.

In order to pull the head rest frame along the side rails 33 of the lifting frame toward the head end of the latter, hauling lines 60 are connected to the cross rail 53 and wound on a roller 61 supported by the end rails 34, the ends of the roller being equipped with crank handles 62 for operating the same. Thus, if the patient slips down toward the

foot of the bedstead, he can be readily brought back.

65

I claim:

1. The combination of a cylindrical pedestal, a hollow plunger slidably mounted in the pedestal, a top plate carried by the plunger, a bedstead swiveled to the top plate to swing in a horizontal plane, a cross-bar in the plunger and having a nut at its center, a non-traveling screw mounted in the pedestal and threaded through the nut, and means for operating said screw. 75

2. The combination with a bedstead having side rails, corner posts and top cross-rails connecting the corner-posts, of a lifting frame slidably mounted on the corner posts, sheaves carried by the cross-rails, hoisting lines passing over the sheaves and connected to the lifting frame, rollers extending transversely between the side rails, around which rollers the hoisting lines are wound, guide pulleys adjacent to the ends of the side rails 80 over which guide pulleys the hoisting lines pass to the rollers, and means for operating the rollers. 85

3. The combination with a bedstead having side rails, corner posts and top cross rails connecting the corner posts, of a lifting frame slidably mounted on the corner posts, sheaves carried by the cross rails, hoisting lines passing over the sheaves, resilient connections between the hoisting lines 90 and the lifting frame, rollers extending transversely between the side rails, around which rollers the hoisting lines are wound, guide pulleys adjacent to the ends of the side rails over which guide pulleys the hoisting lines 95 pass to the rollers, and means for operating the rollers. 100

4. The combination with a bedstead having corner posts, of a lifting frame slidably mounted on said posts, raising and lowering means for the frame, rollers carried by the frame on opposite sides thereof, a sheet wound on the rollers, and means for operating said rollers. 105

5. In a bedstead, a head rest frame having side rails, supporting side rails on which the side rails of the head rest frame are slidably mounted, and a hauling device connected to the head rest. 110

6. In a bedstead, a head rest frame and having side rails provided with apertures, resilient upwardly extending strips seating in the apertures, means for holding the strips, and a covering between the side rails and the strips. 115

In testimony whereof I affix my signature in presence of two witnesses.
